STOKER

Scott Van Etten, Columbus, Ohio

Application August 1, 1940, Serial No. 349,177

1 Claim. (Cl. 83—93)

This invention relates to mechanical stokers.

In such stokers, it is desirable that the coal supplied be suitably fine in order that it shall be readily combustible at the burner. Coal of the bituminous variety often comes in lumps of not freely burnable size mixed with dust, the latter being sometimes called slack.

The principal object of the present invention is to provide a stoker of improved construction with means therein adapted to largely first separate the dust or small portions of the coal from the large and subject the latter to a crushing effect prior to its discharge to the feed worm and trough. Other objects will appear from the disclosure herein.

The invention is embodied in the example herein shown and described, the feature of novelty being pointed out in the claim.

In the accompanying drawing—

Figure 1 is mainly a view in side elevation broken out to show details.

Fig. 2 is a top plan view.

Fig. 3 is an elevation viewed from the right hand side of Fig. 1.

Fig. 4 is a vertical section on the line IV—IV, Fig. 1.

Fig. 5 is a face view of the rotary crusher; and Fig. 6 is an edge view of the same.

In the views, the character 10 designates the hopper which generally, is in the form of a box of sheet metal having a cover 11 hinged at 12 to the top of the hopper. The said hopper has generally speaking a tapered V-shaped bottom portion shown as terminating in a trough 13 that leads into one end of a fuel delivery pipe 14 having at its other end a burner 15. In the said trough and feed pipe is a feed worm 16 operated by suitable power to cooperate in moving the fuel from the hopper to the burner.

Secured at a suitable slant in the hopper is a screen or grid 17 including a series of parallel bars suitably spaced for the purpose of appropriately separating or screening the coal that is thrown onto it into large and small portions. It will be observed that said screen 17 extends slantingly downward from the rear wall of the hopper above the feed worm 16 to the forward

portion of the hopper to the crushing burs so that most of the fine fuel falls into the feed trough in advance of the fractured lumps of fuel.

Arranged in the lower or tapered portion of the hopper is a pair of suitable burs or crushing rolls 18 and 19 as shown in Fig. 1. The burs or roll 18 are preferably fixed so that its bevel rim is flush with the incline of the screen while the cooperating roll 19 is journaled and provided with any suitable and obvious electric motor 20 protected by a hood 25 and gearing for rotating it. The axis of the burs is substantially parallel to the axis of the feed worm 16.

Operated by the same power that operates the crushing roll 19 is a fan blower 22 for supplying air through a pipe to the burner. Connected with the burner is a return pipe 24 employed as a clean out.

In practice when the coal is thrown onto the screen, the dust and smaller portions drop into the trough at the bottom of the hopper while the larger pieces are pulverized by the crushing rolls also fall into said trough, and both portions are fed from the trough by the feed worm to the feed pipe leading to the burner.

The forms and dimensions of the parts can be changed without departing from the gist of the invention as claimed.

What I claim is:

30 A coal stoker including, in combination, a hopper having a V-shaped portion formed as a trough at its bottom extended from front to rear of the hopper, a coal feeding worm in said trough and means for rotating the same, a coal screen in said hopper above said feed worm extending slantingly downward from the rear portion of the hopper over said trough and above the rearwardly coal feeding portion of said feed worm to discharge coal dust and small particles into said trough and onto the rear portion of said feed worm, and a pair of cooperating fuel fracturing burs in said hopper at the base of said screen, one of which burs has its axis of rotation parallel to the axis of rotation of the said feed worm.

SCOTT VAN ETEN.
